UNITED STATES PATENT OFFICE.

VICTOR H. JENNINGS, OF WORCESTER, MASSACHUSETTS, ASSIGNOR, BY MESNE ASSIGNMENTS, TO FRANK R. BATCHELDER, OF WORCESTER, MASSACHUSETTS.

WOVEN POCKETED CARRIER.

1,352,133.

Specification of Letters Patent. Patented Sept. 7, 1920.

Application filed August 14, 1917. Serial No. 186,214.

To all whom it may concern:

Be it known that I, VICTOR H. JENNINGS, a citizen of the United States, residing at Worcester, in the county of Worcester, State 5 of Massachusetts, have invented a certain new and useful Improvement in Woven Pocketed Carriers, of which the following is a specification, reference being had therein to the accompanying drawings.

10 The invention comprises improvements in woven pocketed carriers of the general class embracing cartridge carriers, hospital corps belts, and medical officers' belts, as well as various other carriers having special adaptations. It comprises also a novel pocketed web for use in the making of pocketed carriers, and a novel woven pocket-blank.

15 The invention has for one object thereof the production of woven carriers having perfectly square square-bottomed pockets: that is, pockets adapted to present in their expanded state flat or substantially flat square-cornered bottoms or floors. As produced in practice heretofore, woven pockets of the so-called square-bottomed type usually have the opposite end-portions of a pocket-bottom so combined with adjacent portions of the pocket at the right and left 20 sides of a pocket, and so bound thereto in the weaving, that it is practically impossible to push the bottom down and get it perfectly flat and square at its ends. The invention remedies this fault or defect and 25 the resulting disadvantages.

30 Other important objects of the invention, and results and advantages attained by the invention, are indicated later herein.

35 The improvements in woven pocketed carriers consist in a pocket-bottom web-portion having at its opposite ends terminal edges which are not integrally bound-in in the finished pocket, and side-wall web-portions having lower edges or ends, preferably selvaged, which are non-continuous with the 40 pocket-bottom ends and are not integrally bound-in in the finished pocket. The said side-wall web-portions constitute the side-walls of a pocket. They are of a measurement from upper edge to lower edge corresponding to the depth of the pocket from 45 pocket-mouth to pocket-bottom or floor. The pocket-bottom web-portion constitutes

50 the bottom or floor of the pocket. It is of a length between its opposite terminal edges 55 corresponding to the width of the pocket. The features just mentioned permit the lower portion of a pocket to expand fully 55 into a square-cornered form with the end-portions of the pocket-bottom or floor in, 60 or substantially in, the same plane with the remainder of the pocket-bottom. In finishing 65 a pocket the terminal edges at the ends of the pocket-bottom preferably, though not necessarily in all cases, are united to the 65 lower edges or bottom ends of the pocket side-walls by means of applied fastenings, preferably in the form of stitched seams, to close the openings which otherwise would 70 exist at the said corners. In some cases, 70 however, the proximate edges of the pocket-bottom and pocket-side-walls may be left 75 not fastened together.

80 The pocketed web which constitutes a portion of the invention comprises a plurality of woven pockets embodying the foregoing improvements, joined together in a continuous series as woven. A special feature of invention which is embodied in the 85 said pocketed web and in the respective pocket-blanks which make up such web is a pocket-bottom which is woven folded longitudinally upon itself, with the distinct edges aforesaid at opposite ends thereof. The 90 weaving of the pocket-bottom web-portion 85 with a longitudinal fold provides in simple and convenient manner for making a pocket-bottom of any required total width when 95 opened out flat.

100 The invention produces a carrier-pocket of simplified woven structure and general construction. The said pocket may be woven of large fullness or capacity from back to front more conveniently than pockets of the constructions heretofore usual. The invention 105 simplifies the operations of weaving, so that the rate of production is increased, and so that such operations may be performed, and the improved pocketed-fabric structure produced, by means of simpler loom mechanism than that which has been required heretofore for the weaving of pocketed carriers. The weaving may be performed with pattern devices having much less extensive and elaborate arrangements of indicators, etc., than heretofore

necessary. The manufacture of pocketed carriers in conformity with the present invention may be carried on by operatives less highly skilled than those heretofore 5 found necessary to be employed.

In practising the invention, the form and proportions of the pockets which are produced may be modified variously in practice. Such pockets may be made of uniform 10 capacity at top and bottom, or by the utilization of known principles of weaving may be given a flaring shape so as to render them larger at the top than at the bottom, or vice versa.

15 Pocketed carriers made in conformity with the invention may comprise either a single pocket, as in the case of a first-aid pouch, a knapsack, etc., or a series of pockets, as in the case of cartridge-carriers, hospital 20 corps belts, etc.

Figure 1 of the drawings shows in perspective a two-pocket section of a multiple-pocket woven carrier furnished with finished pockets embodying features of the invention, the pocket-covers or flaps and a portion 25 of one pocket being partly broken away.

Fig. 2 is a face view, in perspective, of a corresponding portion of a pocket-web, as produced in a loom but with a small part 30 broken away so as to illustrate the infold of the pocket-bottom.

Fig. 3 is a back view of the said portion of the pocket-web.

Fig. 4 is a view of a portion of the said 35 pocket-web in section along the infold.

Fig. 5 is a face view showing a modification.

In the drawings, 1, 1^a, 1^b, designate portions of the body-web or band of a woven 40 carrier and 1^c, 1^e, Figs. 2, 3, and 4 are portions of said body-web or band constituting pocket-backs. The portions 1, 1^a, 1^b, are 45 the portions of said body-web or band which adjoin or intervene between the pockets. 3, 3, are pocket-fronts. 4, 4, are pocket-bottoms which respectively are integral with the lower portions of the front and back of a pocket. 5, 5^a, are pocket-side-walls which respectively are integral with the back and 50 the lateral portions of the front of a pocket. Portions of pocket-covers or flaps 6, 6, are shown in Fig. 1, these being connected with the carrier in this instance by having their 55 attaching end-portions inserted into a housing-slit 7 in the top margin of the body-web or band, and made secure therein by suitable fastenings, usually stitches (not shown). The general features of construction thus far referred to resemble what is usual in the 60 art and are not in themselves part of the invention.

Fig. 1 shows finished pockets in an expanded state, with flat or substantially flat 65 and square-cornered bottoms or floors 4, 4, that are produced in accordance with the

invention. It shows also the distinct lower edges 5^b, 5^d, of the side-wall web-portions 5, 5^a, as well as the end-margins 4^a, 4^a, of the pocket-bottom web-portions 4, 4, and represents the said lower edges as secured 70 to the said end-margins by stitches 8, 8, forming stitched seams extending along the meeting edges. In this instance, the respective side-wall and pocket-bottom web-portions 5, 5^a and 4 are substantially rectangular, so that the expanded pockets are 75 rectangular, in cross section, and of uniform capacity at top and bottom.

Figs. 2, 3, and 4 show one mode of producing the pocket-bottom portions 4, 4, with 80 distinct terminal edges at their opposite ends, and one mode of producing the side-wall web-portions 5, 5^a, with distinct lower edges which are non-continuous with the said pocket-bottoms, and which in this 85 instance are selvaged. A second mode of producing the pocket-bottom web-portions with the said distinct terminal edges at their opposite ends is shown by Fig. 5.

Referring first to Figs. 2 and 3, the weaving process involves first the weaving of a portion, as 1, of the body-web or supporting-band, followed by the production of one side-wall web-portion, as 5, of a pocket by interweaving weft or filling with the warp-threads of such web-portion, while the weaving of other portions of the carrier is suspended. Web-portion 5 is woven as a flat web with opposite selvaged edges, of a width from one of such edges to the other 90 corresponding with the required depth of the pocket from pocket-mouth to pocket-bottom. After a sufficient length of this flat web to constitute a side-wall for a pocket of the desired capacity from back to front 95 has been produced separately, the weaving of the pocket-front, folded pocket-bottom, and pocket-back, jointly or concurrently, is begun. The pocket-front is a continuation 100 of the same ply as the side-wall web-portion 110 5. The pocket-bottom and pocket-back are produced by the use of additional sets of warp-threads. In Figs. 2 and 3 the pocket-bottom is woven with an infold. The wefting in the case of such views involves a pick 115 of weft or filling in the direction from the pocket-mouth to the pocket-bottom through a shed in the warp-threads of the pocket-front, then a pick in the reverse direction through a shed in the warp-threads of the 120 upper half of the pocket-bottom, then a pick in the first direction through a shed in the warp-threads of the lower half of the pocket-bottom, then a pick in the reverse direction 125 through a shed in the warp-threads of the pocket-back, and then picks made through sheds formed in reverse order in the pocket-back, lower and upper halves of the pocket-bottom, back to the starting point, and so on. When a sufficient length of web for a 130

5 pocket of the desired size from side to side has been produced, the interweaving of weft or filling with the warp-threads of the pocket-back and pocket-bottom is suspended, 5 while the interweaving of the weft or filling with the warp-threads of the pocket-front is continued to produce the second side-wall web-portion, 5^a, with opposite selvage edges. When the said web-portion has been 10 made of the desired length, the weft or filling is interwoven with the various sets of warp-threads suitably to produce the adjoining portion, as 1^a, of supporting-band or body, following which the leading side-wall web-portion, 5, of the next pocket is produced, and so on.

As woven, the pocket-web is in a flattened state, with the different layers or plies lying close together, one above another, as in Figs. 2 and 3. Between the pocket-bottom web-portion 4 of one pocket and that of the next pocket the warp-threads 4^c of the said web-portions 4 are floated without being regularly bound into the pocket-web, so that 25 upon the completion of the weaving operation, the cutting or breaking of the said warp-threads will permit the sides of the folded pocket-bottom to open away from each other as the pocket is expanded to 30 dimensions corresponding with those represented in Fig. 1. Since the folded pocket-bottom is inclosed between the pocket-front and pocket-back in the case of a pocket-web produced with an infolded pocket-bottom 35 as in Figs. 2 and 3, as shown in the said figures and also in the sectional view, Fig. 4, it is convenient to so control the floated warp-threads 4^c in the weaving that at an intermediate point between one pocket-bottom 40 and the next they shall be carried through to one of the outer surfaces of the pocket-web and there exposed so as to facilitate cutting or breaking them to provide for the expanding of the pockets as aforesaid. 45 In Figs. 3 and 4 the floated warp-threads are shown thus exposed, at 4^d, upon the rear surface of the pocket-back, in loops or floats of a length sufficient to permit a cutting blade or other parting instrument to be inserted under them.

Fig. 5 shows a modification in which the pocket-bottoms are produced with an out-fold, instead of an infold. In this modification the folded pocket-bottoms extend outward, with their upper and lower halves, respectively, in the same planes with the pocket-front and pocket-back, respectively. The floated portions, 4^c, of the warp-threads of the said pocket-bottom lie beyond the adjacent edge of the supporting-band or body-web, so that they are exposed to view and conveniently accessible. In the case of this modification, the cycle of picks in wefting is smaller than in the case of that illustrated in Figs. 2, 3 and 4. Thus a pick is

made from the pocket-mouth through a shed in the warp-threads of the pocket-front and upper half of the pocket-bottom, followed by a pick in the reverse direction through a shed in the warp-threads of the lower half 70 of the pocket-bottom and of the pocket-back, succeeded by picks in the reverse directions through sheds formed in the reverse order in the pocket-back and lower half of the pocket-bottom, and in the pocket-front and 75 the upper half of the pocket-bottom, back to the starting-point, and so on.

In some cases I contemplate providing the pockets with one or more partitions according to the invention set forth and claimed 80 in U. S. Letters Patent for impts. in woven carriers, No. 1,275,436 granted under date of Aug. 13, 1918, upon my application filed May 7, 1917, Serial No. 167,092, namely, by weaving the respective side-wall web-portions of sufficient length to enable such web-portions to be doubled inward toward each other in vertically extending folds having the two sides of each thereof secured together flatwise, and with the inner portions 85 of the two opposite folds secured together.

What is claimed as the invention is:

1. A woven carrier having a square-bottomed pocket comprising pocket-front, pocket-bottom, pocket-back, and side-wall 95 web-portions, all woven in one piece, with said side-walls formed with lower edges corresponding in direction with the top edge of the pocket at a distance therefrom determining the height of the pocket, and said bottom 100 extending beyond said lower edges and formed with terminal ends at an angle to said lower edges of the side-walls, and united thereto by applied fastenings, thereby forming at the ends of the pocket-bottom corners 105 projecting forward from the pocket-back and disposing the said bottom at angles with the front and back so as to square the pocket.

2. A woven carrier having a square-bottomed pocket comprising pocket-front, 110 pocket-bottom, pocket-back, and side-wall web-portions, all woven in one piece, with said side-walls formed with lower edges corresponding in direction with the top edge of the pocket at a distance therefrom determining the height of the pocket, and said bottom 115 extending beyond said lower edges and formed with terminal ends at an angle to said lower edges of the side-walls, and united thereto by stitched seams, thereby 120 forming at the ends of the pocket-bottom corners projecting forward from the pocket-back and disposing the said bottom at angles with the front and back so as to square the pocket.

3. A woven carrier having a square-bottomed pocket comprising pocket-front, pocket-back, pocket-bottom and side-wall web-portions, all integrally united with one another in the weaving, the pocket-bottom 130

web-portion having terminal edges at its opposite ends and the side-wall web-portions having selvaged lower edges corresponding in direction with the pocket-top and determining the height of the pocket, with the said ends secured by applied fastenings to the said selvaged lower edges.

4. A woven carrier having a square-bottomed pocket comprising pocket-front, 10 pocket-back, pocket-bottom and side-wall web-portions, all integrally united with one another, the pocket-bottom web-portion having terminal edges corresponding in direction with the pocket-top and determining 15 the height of the pocket at its opposite ends and the side-wall web-portions having selvaged lower edges, with the said ends secured by stitched seams to the said selvaged lower edges.

20 5. A woven pocketed carrier having a pocket formed with a pocket-bottom web-portion with terminal edges that project forward from the pocket-back, and side-wall web-portions which are integral with the 25 pocket-back and pocket-front but with their lower ends non-continuous with the pocket-bottom ends and corresponding in direction with the pocket-top and determining the 30 height of the pocket, and having said lower ends united by fastenings to the said pocket-bottom ends.

35 6. A woven pocketed carrier having a pocket formed with a pocket-bottom web-portion with terminal edges that project forward from the pocket-back, and side-wall web-portions which are integral with the 40 pocket-back and pocket-front but with their lower ends non-continuous with the pocket-bottom ends and corresponding in direction with the pocket-top and determining the 45 height of the pocket, and having the said lower ends united by stitched seams to the pocket-bottom ends.

50 7. A woven pocketed carrier having a pocket formed with a pocket-bottom web-portion with terminal edges that project forward from the pocket-back, and side-wall web-portions which are integral with the 55 pocket-back and pocket-front and are formed with selvaged lower ends corresponding in direction with the pocket-top and determining the 60 height of the pocket, and having such lower ends united by fastenings to the ends of the pocket-bottom.

55 8. A woven pocketed carrier having a pocket formed with side-wall web-portions which are integral with the pocket-back and pocket-front and are formed with selvaged lower ends corresponding in direction with 65 the pocket-top and determining the height of the pocket, and having such lower ends united by fastenings to the ends of the pocket-bottom.

9. A woven pocketed carrier having a 65 pocket in which the side-wall web-portions of

the pocket are integral with the pocket-back and pocket-front and are formed with selvaged lower ends corresponding in direction with the pocket-top and determining the height of the pocket, with such ends united 70 by stitched seams to the ends of the pocket-bottom.

10. A woven pocketed carrier having a pocket formed with side-wall web-portions which are integral with the pocket-back and 75 pocket-front but with their lower ends, as woven, separate from the pocket-bottom ends and corresponding in direction with the pocket-top and determining the height of the pocket, and having the said lower 80 ends united by applied fastenings to the pocket-bottom ends.

11. A woven pocketed carrier having a pocket formed with side-wall web-portions which are integral with the pocket-back and 85 pocket-front, but with their lower ends, as woven, separate from the pocket-bottom ends and corresponding in direction with the pocket-top and determining the height of the pocket, and having the said lower 90 ends united by stitched seams to the pocket-bottom ends.

12. A woven pocketed carrier having a pocket formed with side-wall web-portions which are integral with the pocket-back and 95 pocket-front but with their lower ends non-continuous with the pocket-bottom ends and corresponding in direction with the pocket-top and determining the height of the pocket, and having the said lower ends 100 united by fastenings to the said pocket-bottom ends.

13. A woven pocketed carrier having a pocket formed with side-wall web-portions which are integral with the pocket-back and 105 pocket-front but with their lower ends non-continuous with the pocket-bottom ends and corresponding in direction with the pocket-top and determining the height of the pocket, and having the said lower ends 110 united by stitched seams to the pocket-bottom ends.

14. A woven pocketed carrier having a pocket formed with a pocket-bottom web-portion with terminal edges that project forward from the pocket-back, and side-wall web-portions which are integral with the 115 pocket-back and pocket-front but with their lower ends non-continuous with the pocket-bottom ends and corresponding in direction with the pocket-top and determining the height of the pocket, 120 with the pocket-top and determining the height of the pocket.

15. A woven pocketed carrier having a pocket formed with a rectangular pocket-floor with distinct terminal edges at its ends, 125 and side-wall web-portions which are integral continuations of the pocket-front and are united integrally with the pocket-back, but with their lower ends non-continuous with the pocket-bottom ends and corre- 130

- sponding in direction with the pocket-top and determining the height of the pocket.
16. A pocket-web consisting of a plurality of woven pockets, each pocket comprising a pocket-back, a pocket-front, a pocket-bottom having terminal edges that project at an angle from the pocket-back to the pocket-front, and side-wall web-portions at opposite sides of each pocket-front, said side-wall web-portions having distinct lower edges corresponding in direction with the pocket-top and determining the height of the pocket.
17. A pocket-web consisting of a plurality of woven pockets, each pocket comprising a pocket-back, a pocket-front, a pocket-bottom having terminal edges that project at an angle from the pocket-back to the pocket-front, and side-wall web-portions at opposite sides of each pocket-front, said side-wall web-portions having selvaged lower edges corresponding in direction with the pocket-top and determining the height of the pocket.
18. A pocket-web consisting of a plurality of woven pockets, each pocket comprising a pocket-back, a pocket-front, a pocket-bottom folded longitudinally upon itself and formed with distinct edges at opposite ends of each pocket-bottom, and side-wall web-portions at opposite sides of each pocket-front, said side-wall web-portions having distinct lower edges corresponding in direction with the pocket-top and determining the height of the pocket.
19. A pocket-web consisting of a plurality of woven pockets, each pocket comprising a pocket-back, a pocket-front, a pocket-bottom folded longitudinally upon itself and formed with distinct edges at opposite ends of each pocket-bottom, and side-wall web-portions at opposite sides of each pocket-front, said side-wall web-portions having selvaged lower edges corresponding in direction with the pocket-top and determining the height of the pocket.
20. A pocket-web consisting of a plurality of woven pockets, each pocket comprising a pocket-back, a pocket-front, a pocket-bottom folded longitudinally upon itself and formed with distinct edges at opposite ends, and with the warp-threads of the pocket-bottoms floated from one of the latter to the next, successively, and side-wall web-portions at opposite sides of each pocket-front, said side-wall web-portions having distinct lower edges corresponding in direction with the pocket-top and determining the height of the pocket.
21. A pocket-web consisting of a plurality of woven pockets, each pocket comprising a pocket-back, a pocket-front, a pocket-bottom folded longitudinally upon itself and formed with distinct edges at opposite ends, with the warp-threads of the pocket-bottom floated from one of the latter to the next, successively, and side-wall web-portions at opposite sides of each pocket-front, said side-wall web-portions having selvaged lower edges corresponding in direction with the pocket-top and determining the height of the pocket.
22. A woven pocket-blank comprising a pocket-back, a pocket-front, a pocket-bottom folded longitudinally upon itself, and side-wall web-portions at opposite sides of the pocket-front, joining the latter to the pocket-back, said side-wall web-portions having selvaged lower edges corresponding in direction with the pocket-top and determining the height of the pocket.

In testimony whereof I affix my signature in presence of two witnesses.

VICTOR H. JENNINGS.
